UNITED STATES PATENT OFFICE.

VICTOR F. LASSAGNE, OF CHICAGO, ILLINOIS.

SUBSOIL PACKER.

Application filed October 31, 1923. Serial No. 671,915.

To all whom it may concern:

Be it known that I, VICTOR F. LASSAGNE, a citizen of the United States, residing at Chicago, in the county of Cook and State 5 of Illinois, have invented certain new and useful Improvements in Subsoil Packers, of which the following is a full, clear, and exact specification.

This invention relates to improvements in 10 tillage tools and more particularly to soil pulverizers and sub-soil packers.

In machines of the type having a lower, or implement, frame including pulverizing rollers and an upper, or draft, frame with 15 which the implement frame is connected for rocking movement, it is desirable to provide a form of flexible or rocking connection between the frames that will so transmit the tractive force and weight from the upper 20 frame to the rollers, or equivalent tools, as to give maximum pulverizing and packing effects and at the same time afford easy traction and smooth riding. Those are the objects of this invention, and they have been 25 attained by employment of a novel form of flexible connection between the frames comprising, in the specific form herein disclosed, of intersecting supporting bars which are 30 bodily movable with respect to each other and each of which is pivoted to the respective frames in substantially the same vertical planes with the axes of the rollers. Also, by incorporating in the structure novel 35 means whereby the tractive force can be variably applied to the rollers as may be necessary for best results with different soil conditions, said means comprising members arranged to transmit a draft thrust to the 40 front rollers.

The invention, therefore, resides in the organization and details of construction, or equivalents thereof, hereinafter more particularly described.

Referring to the drawings—

Fig. 1 is a side elevation of an implement comprising the invention;

Fig. 2 is a plan view of one end of the same;

Fig. 3 is a similar front view;

Fig. 4 is a sectional plan view through the connecting members;

Fig. 5 is a side elevation showing the change in relation of elements when passing over an obstruction;

Fig. 6 is a side elevation of a modified construction; and

Fig. 7 is a similar view with the front roller in different adjustment.

In the present instance the invention is illustrated in connection with a land packer or pulverizer having parallel disk rollers 10, 11, the axles of which are connected at each end by links 12, which, together with the axles, constitute the implement frame. It is preferable that the forward disk roller 10 be of larger diameter than the rear roller, as shown in the drawings, and that the respective disks composing the front and rear rollers be arranged in alternating relation as usual in this type of machine. The implement frame is connected to and supports an upper or draft frame 13 which is provided with the usual centrally positioned draft tongue 14 and with end brackets 15 connecting the ends of the transverse members of the frame. A flexible supporting connection is provided between each end of the upper and lower frames, each of which comprises a pair of supporting bars 16, 17, the bar 17 being connected to the rear end 60 of bracket 15, and the bar 16, to the forward end. The bars 16, 17 extend in opposite directions in intersecting relation, as shown on the drawing, and, in the species of Figs. 1 to 5, the forwardly extending bar 17 is provided with a journal sleeve 18 which receives the axle of the front roller. Similarly, bar 16 extends rearwardly and has a journal sleeve 19 receiving the rear roller, each of the sleeves 18, 19 being preferably 65 positioned between the end disks and the ends of the link 12. In order to provide for variation in the direction of draft thrust applied to the axle of the front roller through bars 17, provision is made for connecting the rear end of each bar 17 adjustably on brackets 15. In the present instance, this means is shown as consisting of a series of openings 20 formed in a depending portion 21 of the brackets 15. The openings 20 are arranged in an arc about the axis of the front roller, and the bars 17 can accordingly 70 be pivoted in either of the openings 20 simply by removing the pivot pins 22 which connect the bars to brackets 15, moving the end of bars 17 to any opening desired, and inserting the pivot pins in the selected openings.

In Figs. 6 and 7 there is illustrated a modified construction which retains the general relation of elements above described but in which the end members or links 12 are

replaced by modified links 23 which are formed near the forward ends with pivot ears 24, to which the lower ends of bars 17 are pivoted instead of on the axle of the 5 roller as in the previous construction. In this form each end member or link 23 is provided with means at its forward end by which the axle of the front roller may be set or positioned at variable points on the forward 10 end of the link 23. In the present instance such means is provided by forming each link 23 with a forward and upward extension 25 in which there is a series of bearings 26, in any one of which the axle 15 of the front roller may be received and retained. The retaining means consists of a removable member 27 which forms the lower half of the extension 25 and of the bearings and is held in position by bolt 28 at its forward 20 end and by an under-cut engagement with the body of link 23 at its rear end, as at 29. The direction of adjustment for the front roller is therefore generally vertical and in a line oblique to the longitudinal axis 25 of the link 23, thus providing for adjustment of the roller in an upward and downward as well as forward direction with relation to the point of draft application or propelling force applied to ears 24. It is accordingly 30 possible to place the roller axle in the rear one of the bearings 26 and directly beneath ears 24, as in Fig. 6, in which case the thrust of the draft would be applied directly above the axle, or, in any of the forward openings, in which cases the draft would be applied practically in line with or below the 35 axle, the highest upward adjustment of the forward roller with respect to the pivot of links 17 on ears 24 being shown by Fig. 7.

40 Preferably, adjustment for the upper end of bars 17 is also provided, but in this species the arc of adjustment is about the pivot to ears 24.

45 It will be understood that flexible supporting means between the upper and lower frames, such as just described, are provided at each end of the frames and that they are, of course, exactly alike, and that in either of the species of the invention above described the implement frame in which the 50 rollers 10 and 11 are comprised is freely movable with respect to the upper frame, the supporting members moving with relation to one another, as illustrated in Fig. 5, when passing over uneven surfaces.

55 With the constructions described it will be evident that the respective rollers rise and fall with respect to each other as they ride over clods and rough ground during 60 operation and that the movements of the crossed supporting members 16, 17 will be such as to cause the weight of the upper frame to be lifted when either roller passes over a rise or obstruction in its path. For 65 example, when the front roller moves up, as

in Fig. 5, its axle must move in an arc about pivot pins 22 as a center, but as the front axle is tied to the rear axle by the end members or links 12 an upward thrust is imparted to bars 16 and to the upper frame. 70 The higher the upper ends of bars 17 are set in the brackets 20, the more lifting effect there will be on the upper frame and the greater the crushing effect of the front roller, both by reason of the weight moved 75 and by reason of the direction of the draft thrust applied to the front roller through bars 17, this thrust becoming more effective as the inclination of bars 17 is increased by 80 placing their pivot point higher on the 85 brackets. In the species of Figs. 6 and 7 where adjustment for the front roller in a forward and upward direction is provided, this too has the effect of varying the direction of the draft thrust or pressure applied thereto. The more the front roller axle is placed forward and above the point of draft application, as illustrated by Fig. 7, the easier the front roller will ride over obstructions and the less will be its tendency 90 to dig in when on loose or fluffy soil, the effect of such adjustment of the roller being somewhat analogous to that obtained by lowering the handles of a wheelbarrow that is being propelled over a rough or a soft 95 surface. Obviously, front roller adjustment on the end members of the implement frame, such as just described, is applicable with the same effect to any land packer or pulverizer having a rocking roller frame and a point of draft application above or behind the front roller axle, irrespective of the particular rocking connection between the upper and lower frames, but, when employed with pivoted crossed members having adjustment as herein disclosed, a greater range 100 of variation in the roller action to suit various soil conditions becomes possible.

105 The constructions and arrangements herein described are the preferred embodiments of the invention, but it will be evident to those skilled in the art that several other practical forms thereof are possible within the scope of the following claims.

110 Having described the invention, what is claimed is:

1. An implement comprising the combination of upper and lower frames, a pair 115 of parallel roller carrying shafts comprised in the lower frame, and means connecting the ends of the frames for rocking movement in the direction of travel comprising a pair of crossed supporting bars the ends of which are pivoted to the respective frames, one of said points of pivotal connection being adjustable.

120 2. An implement comprising the combination of upper and lower frames, a pair 125 of parallel roller carrying shafts comprised in the lower frame, and means connecting

- the ends of the frames for rocking movement in the direction of travel comprising a pair of crossed supporting bars the ends of which are pivoted to the respective frames, the pivotal connection between one of the said bars and the upper frame being adjustable in a vertical plane.
3. An implement comprising the combination of upper and lower frames, roller carrying shafts comprised in the lower frame, and means connecting the frames for rocking movement in the direction of travel comprising pairs of crossed supporting bars pivoted to the respective frames.
- 10 4. An implement comprising the combination of upper and lower frames, soil working means carried by the lower frame, and pivoted supporting means connecting the frames for rocking movement in the direction of travel comprising intersecting bars pivoted to the respective frames.
- 15 5. An implement comprising the combination of upper and lower frames, soil working means carried by the lower frame, and means connecting the frames for rocking movement comprising oppositely directed members each of which is pivoted to the respective frames at opposite front and rear points.
- 20 6. An implement comprising the combination of a lower frame, soil working means carried by the lower frame, and an upper frame supported on the lower frame by means permitting rocking movement between the frames and comprising a plurality of movable members each of which is pivoted to both frames.
- 25 7. An implement comprising the combination of a lower frame comprising front and rear rollers, and a draft frame supported on the lower frame by flexible means including a connecting bar at each end of the frames pivotally connected at its upper end to the rear of the draft frame and at its forward end to the front of the lower frame.
- 30 8. An implement comprising the combination of a lower frame comprising front and rear rollers, and a draft frame supported on the lower frame by flexible means including forwardly directed thrust members pivoted to the rear of the draft frame and to the forward portion of the lower frame.
- 35 9. A pulverizer comprising the combination of upper and lower pivotally connected frames, front and rear pulverizing rollers journaled in the lower frame, and means for raising and lowering the bear-
- ings of one of said rollers on the lower frame.
10. A pulverizer comprising the combination of upper and lower pivotally connected frames, front and rear pulverizing rollers journaled in the lower frame, and means for raising and lowering the bearings of the forward roller on the lower frame.
- 15 11. A pulverizer comprising the combination of upper and lower pivotally connected frames, the lower frame comprising end members the forward ends of which have upwardly directed portions, a forward pulverizing roller having journals adjustable along said upwardly directed portions of the end members, and a rear roller journaled in said end members.
- 20 12. A pulverizer comprising the combination of an upper frame, a lower frame including end members having a pivotal connection intermediate their ends with the upper frame, front and rear pulverizing rollers journaled in the end members, and means for setting the forward roller on the end members at different points in advance of said pivotal connection between the frames.
- 25 13. A pulverizer comprising the combination of an upper frame, a lower frame including end members having a pivotal connection intermediate their ends with the upper frame, front and rear pulverizing rollers journaled in the end members, and means for effecting adjustment of the forward roller towards and from the forward ends of the end members.
- 30 14. A pulverizer comprising the combination of an upper frame, a lower frame including end members having a pivotal connection intermediate their ends with the upper frame, front and rear pulverizing rollers journaled in the end members, and means for setting the forward roller on the end members at any of a plurality of selected points in advance of said pivotal connection between the frames and on a line oblique to the longitudinal axis of the end members.
- 35 15. An implement comprising the combination of a lower frame comprising front and rear rollers, and a draft frame supported on the lower frame by pivotal connections comprising members pivoted to the respective frames in substantially the same vertical planes with the axes of the rollers.

In testimony whereof I affix my signature.

VICTOR F. LASSAGNE.
